UNITED STATES PATENT OFFICE.

WILLIS MARKER, OF ATLANTA, GEORGIA.

DESIGN FOR A MONUMENT.

49,359.

Specification for Design.

Patented July 11, 1916.

Application filed April 19, 1916. Serial No. 92,324. Term of patent 14 years.

To all whom it may concern:

Be it known that I, WILLIS MARKER, a citizen of the United States, residing at Atlanta, in the county of Fulton and State of Georgia, have invented a new, original, and ornamental Design for Monuments, of which the following is a specification, reference being had to the accompanying drawing, forming a part thereof.

The figure is a perspective view of a monument, showing my new design.

I claim:

The ornamental design for a monument, as shown.

WILLIS MARKER.

Witnesses:

T. S. FIELD,
J. M. SMITH,
H. A. BROCKMAN.
